G. J. BAUER ET AL

LINK FOR EXPANSIBLE BRACELETS

Filed July 26, 1922

A technical drawing of a curved metal component, likely a bracket or a support. The component is U-shaped with a central slot. A vertical rib or support is attached to the inner surface of the U-shape, positioned near the slot. The drawing is labeled with numbers: '2' is at the top right, '3' is on the inner vertical rib, '4' is on the left vertical wall of the U-shape, and '5' is on the bottom horizontal leg of the U-shape.

Fig. A.

A photograph of a book cover. The cover is a light-colored wood-grain material. Handwritten numbers are written on the cover: '27' is written near the spine on the left side, and '28' is written near the spine on the right side, just above the letter 'H'.

A cross-sectional diagram of a cylindrical component. The outermost layer is labeled '3' at the top and bottom. Inside, there are several layers: a top layer labeled '29', a layer labeled '7', a layer labeled '9', a central vertical layer labeled '1', and a bottom layer labeled '2'. The diagram shows a stepped or tapered internal structure.

A technical line drawing of a door assembly. The door is shown in an open position, revealing an interior panel (21) and a lock mechanism (20). A handle (17) is attached to the top edge of the door. A lock body (19) is mounted on the door, with a lock plate (28) and a lock bolt (29) extending from it. A lock cylinder (27) is also part of the assembly. The door is shown in an open position, revealing an interior panel (21) and a lock mechanism (20). A handle (17) is attached to the top edge of the door. A lock body (19) is mounted on the door, with a lock plate (28) and a lock bolt (29) extending from it. A lock cylinder (27) is also part of the assembly.

UNITED STATES PATENT OFFICE.

GEORGE J. BAUER, OF PAWTUCKET, AND FRANK B. CARLSON, OF PROVIDENCE, RHODE ISLAND.

LINK FOR EXPANSIBLE BRACELETS.

Application filed July 26, 1922. Serial No. 577,616.

To all whom it may concern:

Be it known that we, GEORGE J. BAUER and FRANK B. CARLSON, citizens of the United States, residing at Pawtucket and Providence, respectively, in the county of Providence and State of Rhode Island, have invented certain new and useful Improvements in Links for Expansile Bracelets, of which the following is a specification, reference being had to the accompanying drawings.

Heretofore in bracelets of this character coil springs have been used for yieldably connecting the various links, and it has been found that springs of this character are inferior and are not durable due to the bracelet being constantly stretched as a result of it being slipped on and off the hand of the wearer. Springs of such a character break and become weak as a result of such usage, and when broken the bracelet must necessarily be repaired, and when the springs become weak, the bracelet hangs loose upon the wrist of the wearer. Furthermore such springs are housed in the opposite overturned edges of the links of the bracelet, and due to this construction the links more or less bind, therefore do not expand very readily, and as a whole, a bracelet so constructed is more or less very expensive in construction as well as to the customer.

It is, therefore, the purpose of the present invention to provide an expansile bracelet, wherein the construction can be cheaply made, permitting the bracelet to be sold reasonably.

Another purpose is to provide a bracelet of this character, wherein the links are more positively connected and guided relatively to each other, and also wherein flat springs are used, instead of coil springs, so as to connect the links for expansile movement. In fact the flat springs, each comprise a plurality of flat straight portions connected by spring loops, so as to cause the flat portions to relatively spread when the springs are expanded, and to enable them to come together, when the various links of the bracelet are relatively expanded.

A still further purpose is the provision of flat springs constructed of steel, which may be either silver or gold plated interconnecting the links, and thereby providing a structure which is more durable, therefore will withstand the constant expansile ac-

tion of the bracelet, when slipping it on and off and over the hand of the wearer.

A further purpose is the provision of improved connections between the various links for relatively guiding them, and to insure more rigidity between the links, particularly in alignment with each other, and also to provide a bracelet which may be sold reasonably and which will give better results than bracelets heretofore devised.

The invention further aims to provide a bracelet, wherein the two halves of the length of the bracelet are similarly constructed. In other words the construction of one-half is the same as the construction of the other half, only it is reversed or arranged in the opposite direction.

The invention further aims to provide an improved hook or catch or connection between each end of the bracelet and the watch, enabling the watch to be connected more positively and securely to the ends of the bracelet.

It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-after set forth, shown in the drawings and claimed.

In the drawings:—

Figure 1 is a view in perspective of the improved bracelet constructed in accordance with the invention;

Figure 2 is a plan view of the wrist watch bracelet detached from the watch and shown in plan open up and partly stretched, showing several of the links in section and others in elevation with their springs and link connections in dotted lines;

Figure 3 is a sectional view on line 3—3 of Figure 2;

Figure 4 is an enlarged detail perspective view of one of the links looking toward the under face thereof, showing the overturned guide and abutment flanges;

Figure 5 is a detail perspective view of one of the back plates 27;

Figure 6 is a detail perspective view of one of the loop or open links;

Figure 7 is a sectional view on line 7—7 of Figure 1;

2
Figure 8 is an enlarged detail view in perspective of one of the fastener or hook links, which connects to the wrist watch;

5 Figure 9 is a sectional view on line 9—9 of Figure 6.

Referring to the drawings, 1 designates the plates of the bracelet and 2 the open or loop links. These links are arcuate in shape, that is to say throughout their 10 lengths, and the plates 1 have longitudinal over-rolled side flanges 3, and end abutment flanges 4. The end abutment flanges 4 do not extend the full width of the plates, but are foreshortened as shown. In other 15 words the ends of the end abutment flanges 4 are spaced from the ends of the longitudinal side flanges, thereby permitting the side bars 5 of the open or loop links to guide therethrough. The over-rolled longitudinal 20 side flanges 3 of the plates 1 overlie the back plates 27, which guide the open or loop links 2 in their movements relative to the plates 1.

The back plates 27 are arranged over the 25 open or loop links and act to retain the expandable springs in position, while the over-rolled longitudinal side flanges 3 act to hold the back plates in position. The back plates have end extensions 28, and are provided 30 with longitudinal side flanges 29, which engage between the over-rolled longitudinal side flanges 3 of the plates.

It will be noted that the center plate is longer than the other plates, and that two 35 adjacent loop or open links 7 are much shorter than the other open or loop links 8. The two shorter open or loop links 7 are connected slidably to the opposite ends of the central longer plate, whereas the remaining plates and links are of uniform 40 lengths. Interposed between certain of the abutment flanges 4 and the transverse bar at certain of the ends of the open or loop links are springs 9. These springs 9 are 45 constructed from flat steel or other spring material, which may be either silver or gold plated, or otherwise finished, to prevent corrosion, and to permit the bracelet to be very easily and quickly adjusted when expanded in order to slip over the hand and fit the wrist of the wearer. The springs 9 are arranged in the open or loop links, and certain of the longitudinal over-rolled side 50 flanges 3 of the plates 1 are extended around the side bars 5 of the open or loop links sufficiently to overlie the springs, to retain them in position, and to prevent them from springing out, when the bracelet is removed from the wrist. The springs 9 are 55 constructed from flat spring material, such as steel or the like, and comprise collapsible sections 11, which are integrally connected by the curved or rolled portions 11^a, which act to provide resiliency for the various sections 11 of the springs.

Guided by the longitudinal side flanges 3 of each end plate 1 is a fastener, for connecting the expandable bracelet to the loops 12 of the wrist watch 13. The fastener 14 comprises a main plate 15 provided with a slot 16 and having an elongated opening 17. The side portions of the plate 15 adjacent where the elongated opening 17 is constructed, have their ends connected by a bar 18. The end portions of the sides 19 of the plate 15 are bent over to provide hooks 19^a, which are designed to engage one of the loops 12 of the wrist watch. The fastener also includes a spring tongue 20, and the body portion of this tongue (which is constructed of spring material) is provided with an offset bent part 21, which is fastened in any suitable manner in the slot 16, so that the end portion 22 of the spring plate 20 will overlie the transverse bar 23 of the plate 15. The tongue 20 has an opening 26 and integral with one of the transverse sides of the opening is an extension auxiliary tongue 25, which is curved and extends through the opening 17 of the plate 15 and is spaced from the hooks 19^a in order to retain the transverse rod of the loop 12 in engagement with the hooks 19^a. Obviously by moving the tongue 20 in the direction of the arrow a, the portion of the tongue 20 from where the auxiliary tongue integrally extends, may be moved to disengage the transverse bar 18 of the hooks 19^a, to enable the fastener to disengage the loop 12 of the wrist watch, while either on or off the wrist. The bars of the loops 12 engage between the hooks 19^a and the auxiliary tongue 25, thereby preventing any lost motion of the connecting parts of the wrist watch bracelet. Obviously the bent offset portion 21 of the tongue 20 is contracted, so as to fit in the slot 16 of the plate 15.

In the operation, the fasteners are connected to the loops 12, and by expanding the bracelet, it is obvious that it may be stretched over the hand, so that it may encircle the wrist of the wearer.

While the wrist watch bracelet is described as being slipped over the hand, to be applied to and removed from the wrist, it is the aim of the invention to use the fastener to either side of the watch, for the purpose of applying and removing the bracelet to and from the wrist. In fact by moving the tongue 20 in the direction of the arrow a, as in Figure 7, one or the other of the ends of the bracelet may be detached from the watch or connected thereto, for the purpose of applying the bracelet to the wrist or removing the same.

The invention having been set forth, what is claimed is:

1. In combination, a plate provided with overturned parallel flanges on its longitudinal edges, a pair of loop links slidably en-

- gaged with said flanges, the ends of the plate having overturned flanges of lengths substantially equal to the width between the sides of the loop links, said end flanges 5 engaging between the sides of the loop links, a back plate overlying the adjacent ends of the loop links and engaging under the longitudinal and end flanges.
2. In combination, a plate provided with 10 overturned parallel flanges on its longitudinal edges, a pair of loop links slidably engaged with said flanges, the ends of the plate having overturned flanges of lengths substantially equal to the width between 15 the sides of the loop links, said end flanges engaging between the sides of the loop links, a back plate overlying the adjacent ends of the loop links and engaging under the longitudinal and end flanges, said 20 back plate having end flanges conforming to and engaging the first end flanges, and expandible means between the adjacent ends 25 of the loop links and the end flanges of the back plate.
3. In combination, a plate provided with end flanges, a back plate having end
- flanges engaging under the first end flanges, loop links of widths substantially equal to and receiving the end flanges of the first named plate, means on the longitudinal 30 edges of the plate and overlying said back plate, thereby holding the back plate in place and acting to guide the loop links.
4. In combination, a plate provided with end flanges, a back plate having end flanges 35 engaging under the end flanges of the first named plate, loop links of widths substantially equal to and receiving the end flanges of the plate, means on the longitudinal edges of the plate and overlying said back 40 plate, thereby holding the back plate in place and acting to guide the loop links, and expandible means between one end of one of the loop links and one of the end flanges of the back plate for expansibly and 45 yieldably connecting one of the loop links to the body plate.

In testimony whereof we hereunto affix our signatures.

GEORGE J. BAUER.
FRANK B. CARLSON.
